UNITED STATES PATENT OFFICE.

THOMAS OLIVER COOPER, OF WILMINGTON, DELAWARE, ASSIGNOR OF
ONE-HALF TO JOHN L. HALL, OF SAME PLACE.

ELECTRIC RAILWAY-GATE.

SPECIFICATION forming part of Letters Patent No. 628,393, dated July 4, 1899.

Application filed October 13, 1898. Serial No. 693,408. (No model.)

To all whom it may concern:

Be it known that I, THOMAS OLIVER COOPER, a citizen of the United States, residing at Wilmington, in the county of New Castle and State of Delaware, have invented a new and useful Improvement in Electric Railway-Gates; and I do hereby declare the following to be a full, clear, and exact description of the same, reference being had to the accompanying drawings, in which—

Figure I is a face view of a switchboard to be located in the gear-box of each gate and a plan of a system of rails and connections on a railroad. Fig. II represents a switchboard with trolleys and connections on an engine to engage the said tracks. Fig. III is a side view of a gate raised and its gear-box, certain portions being broken away. Fig. IV is a face view of the operating-disk. Fig. V is an edgewise view of the operating-disk. Figs. VI and VII are detail views showing portions of the gate-switchboard in horizontal section. Fig. VIII is a side view of a trolley.

This invention relates to that class of devices which are designed to operate gates at railway-crossings; and its object is to provide mechanism, including electrical communications, whereby an engineer on an engine may control one gate or a series of gates, including those at every crossing in a town on his track, both to close and to open each and all of the gates at will while his engine is moving either forward or backward or standing still at any point near the gates.

To this end my invention consists in the construction and arrangement of parts forming an electric railway-gate, hereinafter more fully described, and particularly set forth in the claims.

With reference to the drawings, numeral 1 represents a gate to be located at a railway-crossing, 2 a segment of a worm gear-wheel, and 3 an operating-disk, all rigidly mounted on a shaft 4, which is journaled to rotate one-quarter of a revolution to and fro in the gear-box 5 to close and open the gate both by positive action. The gate is balanced by any usual means.

6 is a worm engaging the segment 2, and 7 a gear-wheel upon the worm-shaft.

8 is a worm upon the shaft of the rotary motor 9, and it engages the wheel 7.

10 represents an electrical generator to be located on a locomotive-engine for furnishing electric energy or power for operating all the gates on the railroad-line and for energizing all the electrical appliances used to control the gates.

11 and 12 are pole-changers, and 13 the switch therefor. 15 and 16 are also pole-changers, and 17 the switch therefor.

18 is a link-rod by which the two switches 13 17 may be connected to operate together.

The buttons 14 represent each pole-changer as a rheostat.

19 and 20 are switches permanently connected with a wire 21, that extends to the positive pole of the generator 10.

22 and 23 are switches connected with a wire 24, that extends to the negative pole of the generator 10. Switch 19 may be turned onto either wire 25, 26, or 27, connecting it with wire 21. Switch 22 may connect with wire 25, 28, or 29. Switch 20 may connect with wire 25, 29, or 30. Switch 23 may connect with wire 25, 26, or 27. Wire 31 connects switch 13 with a trolley 33. Wire 32 connects switch 17 with trolley 39.

34, 35, 36, 37, and 38 are trolleys connected, respectively, with wires 30, 29, 25, 27, and 26, and the trolleys have electrical contact with rails 40, 41, 42, 43, 44, 45, and 46, which rails are sufficiently elevated above the road-bed to avoid grounding, yet not above the level of the railway-tracks.

47 is a switch on the gate-switchboard, pivoted at 48 for engagement with spring 49.

50 is a switch pivoted at 51 to engage either spring 52 or 53.

54 is a switch pivoted at 55 and provided with a contact-spring 56 and also with an arm to be engaged by a spring-detent 57. 58 is an elbow-lever pivoted at 59 and provided with a pull-spring 60. The contact-piece 61 is metallic to connect electrically with switch-spring 56 and joined by an insulator 62 with the body of lever 58 as an arm thereof.

63 is a rod of insulating material pivotally connected with switches 47, 50, and 54 and with a lever 64, which is pivoted at 65.

66 is an elbow-lever pivoted at 67, one arm 68 thereof having a raised flange 69 and another arm having a fixed stud 70 to engage a slot in each rod 71 and 72. The rods 71 and 5 63 are pivotally connected at 73.

74 is a switch to engage electrically the spring 76 and pivoted at 75 to be operated by rod 72.

77 is a switch-rod embedded to slide longitudinally in the switchboard 78 and provided with a fixed stud 79, an arm 80, having a wedge 81 at its end, and a connecting-rod 82, of insulating material. An electrical switch-spring 83 is secured upon the switchboard 78, free above the rod 82, and has a wedge 84 to be engaged by the wedge 81 to make contact with switch-lever 66.

85 is an elbow-lever pivotally connected by one arm with the rod 71 and the other arm located to engage stud 79.

86 is an electromagnet fixed on the board 78 and provided with an armature 87, that is connected with rod 82.

88 is an electromagnet on the board 78 and 25 having an armature 89, which is connected by a rod 90 with elbow-lever 66. 91 is another electromagnet on board 78, having an armature 92, connected with an arm of elbow-lever 66 at the opposite side of its pivotal point 30 from rod connection 90 by means of a rod 93 and spring 94.

95 is a switch pivoted to the board at 96, with one end projecting into the path of studs 97 and 98, which are carried by the disk 3.

35 99 is the spring to contact with switch 95. 100 is a switch pivoted to the board at 101, with an end projecting into the path of stud 102, which is on the disk 3, and the other end to contact with spring 103.

40 104 is a retracting-spring for switch 100.

105 is an elbow-lever on the board 78, one of its arms 106 being a stiff spring to engage lever 64.

107 is a hook-detent to engage lever 105.

45 108 is a signal-box having a local battery, a bell 109, and an annunciator 110, the latter of which is pivoted at 112 to be swung up and down in conformity with the action of the gate by a connecting-rod 111. Wires 113 and 50 114 connect the signal-box 108 with the spring 99 and switch 95, whereby a local circuit is completed when the switch is closed. This signaling device may be located at any convenient point to observe the action of a gate 55 or one for each gate in a town. Switch-springs 115, 116, 117, and 118 are located upon the board 78 and permanently connected, respectively, with wires 124, 120, 121, and 122, and those springs are hung to be pushed into contact with points, respectively, of wires 123, 60 155, 125, and 126 by means of a cam 127 upon the disk 3.

128 is a cam on the disk, which presses spring 107 down upon lever 105 as the gate 65 nears the end of its upward course, so that when stud 102 pushes lever 105 back the spring-detent 107 engages and holds it.

129 is a cam on disk 3, which bears spring-detent 57 down as the gate approaches its closed position, so that when the switch 54 is 70 pushed by stud 97 it is caught and held by the detent 57.

130 is an electromagnet mounted on disk 3 and provided with an armature 131, which carries stud 97 to play freely through the 75 disk 3.

132 is a spring to hold armature 131 away from the magnet 130, with stud 97 normally projected for service.

133 and 134 represent signal-bells, each provided with means to be electrically operated and located near the gate.

135 and 136 represent electric lamps to be located upon the gate.

Numbers 137 to 163 represent wire connections for electric communication with parts on the switchboard 78.

The rails described are located along the road-bed far enough at each side of every gate to give due warning and to close the gate 90 before the engine is near enough to render crossing dangerous.

In Fig. VIII, I show one means of hanging the trolleys. Each trolley is mounted to slide vertically in a frame 180, which is loosely hung, by means of trunnions 164, in slots in hangers 165, that are attached to some convenient portion of the engine or tender, so that the frame of trolleys will hang by the springs 166 and trail in either direction when 100 in service. 167 represents a lever by which the fireman may lift the frame of trolleys whenever required, and over long stretches between crossings it is safer to hold the trolleys raised far above the road by securing the 105 lever 167 with a catch 168.

Thus far the description is based on the supposition that wire 169 connects with the positive pole of the generator 10 and 170 with the negative pole. Now the pole-changers 11 110 and 16 being connected by a wire 174 and the changers 12 and 15 by wire 175, if the switches 13 and 17 be turned upon the changers 12 and 16, respectively, the direction of the current will be such that wire 32 will be positive and 115 wire 31 negative. In backing an engine this is not required; but it is required when the engine is turned around to run the other way on the same track.

Operation: Let us suppose an engine provided with an electric generator 10 and the trolleys, switches, and connections described to be moving on the track A in the direction of the arrow a toward gate 1. In order to close the gate, the engineer sets switch 20 125 upon wire 30 and switch 23 upon wire 26. This introduces a current from generator 10 over wire 21, switch 20, wire 30, trolley 34, rail 41, and wire 149 to magnet 86, from which the circuit returns over wire 126, contact-point of 130 spring 118, which is at this time held in contact by segment 127 through the said spring, and over wires 122 and 124, rail 45, trolley 38, wire 26, switch 23, and wire 24 back to the

generator 10, completing a metallic circuit, whereby the magnet 86 is energized and attracts the armature 87 to draw the rod 80, with its wedge 81, against spring 83, bringing it into contact with elbow-lever 66. This is completed in an instant of time, so that the switches 20 and 23 may be immediately returned to their open position, as shown. Now the hand-levers 17 13 may be set in contact 5 with the rheostat-buttons, whereby the current is introduced from generator 10, with any desired degree of force, over wire 169, rheostat 11, lever 13, wire 31, trolley 33, rail 40, wire 145, switch 50, spring 53, and wire 171 to the 10 motor 9, whence the current returns over wire 154, spring 83, which was set in contact with elbow-lever 66, thence over wires 140 and 142, rail 46, trolley 39, wire 32, switch-lever 17, rheostat 15, and wire 170 to the generator 15 20. The circuit being thus complete through the motor 9, it rotates the worm 8, by which spur-gear 7, worm 6, and segment 2 are operated to turn the shaft 4 and with it the gate 1 to close the same. The disk, revolving 25 with the segment 2 and shaft 4, brings pin 97 against the edge of lever 66, pushing the arm 68 to the position shown by dotted lines 172 and raising the other arm of lever 66 and with it the connecting-rods 71 and 63 and setting 30 switches 47 50 in contact with their respective springs 49 and 52, whereby the direction of the path of the current is reversed. This movement also bears the arm 58 upward and the arm 61 to the right and raises the switch- 35 spring 56 into the path of arm 61, as shown in dotted lines, and in raising spring 56 the opposite end of lever 54 is carried under the hook of mechanical spring 57, which at this time is pressed into engagement with the said 40 lever 54 by segment 129 on disk 3, whereby the rods 71 and 63 and the parts directly connected thereto are held stationary. The raising of rod 71 operates lever 85 against stud 79 and draws rod 77 with wedge 81 from spring 45 83 and breaks the contact between the latter and elbow-lever 66, thereby interrupting the generator-circuit. In reaching its present position, with the gate down, the disk 3 has carried the stud 102 against the arm of switch 100 50 and closed the latter with the spring 103. Now to raise the gate the engineer throws switch 17 out of connection and he connects wire 24 with wire 25 by means of switch 22, establishing a circuit which, starting at the generator 10, 55 passes over wire 169, rheostat 11, switch 13, wire 31, trolley 33, track 40, wires 145 and 146—switch 50 53 having been opened by the raising of rod 63—through electromagnet 130, over wire 153, through set switch 100 103, over wire 60 150, rail 43, trolley 36, wire 25, switch 22, and wire 24 back to the generator. The magnet 130 being energized lifts its armature 131 with pin 97, removing the latter from engagement with arm 68, permitting the same to be re- 65 stored to its normal position, as shown in full lines, by means of elbow-lever 58 and spring 60. The flange 69 now stands in front of the

I raised stud 97 to prevent the stud from passing in front of arm 68 under any circumstances, as something would be broken if the 70 gate were to be raised with the pin at the wrong side of that arm. The action of spring 60 on lever 58 also restores the latter to its normal position, as shown in full lines, at the same time making contact with spring 56, which is 75 in the position of the dotted lines, whereby the reverse circuit is completed for operating the motor 9 to raise the gate. To do this, the engineer throws off switch 22, breaking its connection with wire 25, and turns on switch 80 17, whereby the current is turned into circuit, which, starting at the generator 10, passes over wire 169, rheostat 11, switch 13, wire 31, trolley 33, rail 40, wire 145, switch 50 52, and wire 144 to the motor at that pole which was 85 formerly the negative, but now made positive to reverse the action, thence returning over wire 143, switch 54 56 61, wires 141, 140, and 142, rail 46, trolley 39, wire 32, switch 17, rheostat 15, and wire 170 to generator 10. The 90 motor being operated raises the gate by means of the connecting-gearing. The first action of the returning disk 3 is to carry pin 102 away from arm 100, permitting switch 100 to be retracted by spring 104, breaking contact with 95 spring 103. The second action is to carry pin 97 back off from arm 68, when the armature-spring returns that pin to its normal path behind arm 68 and ready to engage it again. The final result is the restoring to their 100 normal positions, as shown in full lines, of rods 71 and 63 and their positive connections, the switches 50 52, 47 49, and 56 61, which are all opened, and the switch 50 53, which is closed, all by the pin 102 acting through lever 105, 105 spring-arm 106, and lever 64 upon the said rod 63. At this time segment 128 on disk 3 presses spring-detent 107 into engagement with arm 105, holding the connected switches from being disarranged. 110

Streets to be crossed in cities are frequently so close together that a second gate, or even a third gate, should be closed before a fast-approaching engine reaches the first gate, so it becomes necessary to form electric connections which pass one or more gates, and yet it is not practicable to continue all the electrical rails through a city, because that would close all the gates by the act of closing one, so that travel on all the streets would be interrupted even though the engine needed to cross only the first street. For this and other reasons I break, as at 173, part of the rails at each crossing and continue other rails past the crossings, and the center rail I break mid-way between crossings. 115 120 125

In my system of construction seven electrical rails are located along between the tracks far enough at each side of every gate to give due warning and to close the gate before an engine can reach there. Three of these rails 40 41 42 are continuous where there are many crossings and serve as conductors from the generator on the engine to the mo- 130

tors which operate gates, one at each crossing. The three corresponding rails 46 45 44 complete the circuits back to the generator and are the ones broken at crossings.

5 In order to complete the circuit for operating the gate by an engine backing from the left toward the gate, the switch 74 76 is provided to operate as follows: First, the switches 20 and 23 are to be set to engage, respectively, 10 the wires 29 and 27, which completes a circuit from generator 10 over wire 21, switch 20, wire 29, trolley 35, rail 42, wire 152 to magnet 88, thence returning over wire 125 and spring 117, which are now in contact, over 15 wires 121 and 120, rail 44, trolley 37, wire 27, switch 23, and wire 24 to the generator. The magnet 88 being energized, attracts armature 89 and mechanically draws the elbow-lever 66, by means of rod 90, farther to the right 20 than it has been heretofore moved, and in so doing draws down rod 72 and sets the switch 74 into engagement with spring 76. The rod 71 is slotted to permit the stud on lever 66 to play down freely, so that said rod 71 will not 25 be moved by setting the switch 74 76. This switch being set completes a circuit which, starting at the generator 10, passes over wire 169, rheostat 11, switch 13, wire 31, trolley 33, rail 40, wire 145, switch 50 53, and wire 171 to 30 the motor 9, and returns over wires 154 and 137, switch 74 76, wires 138 139, rail 46', trolley 39, wire 32, switch 17, rheostat 15, and wire 170 to generator, which energizes the motor 9 to close the gate, as before described. The 35 pin 97 operates elbow-lever 66, and thereby raises rod 72 and opens the switch 74 76 at the same time that certain parts are reset, as before stated. The rod 72 is slotted for the stud on elbow-lever 66 to permit the usual operation at first described without then operating the switch 74 76. The gate is to be opened by exactly the same manipulation as at first described for that purpose, because rail 46' is now connected over wire 139 and 40 the closed switch 47 49 with wire 140, completing the circuit as rail 46 formerly did over wire 142. The rail 45', being connected by wire 123 with the contact-point of spring 115, is in circuit with rail 45 over wire 124 when 45 ever the gate is down, for then the segment 127 holds the spring 115 in contact with that point, thus forming a bridge over the gap 173. A similar result is effected with rails 44' and 44 through their connections 120 and 155 with 50 spring and contact-point 116, that contact being also made by pressure of the same segment 127 at the same time. The gap 173 is made because otherwise all circuits for one gate would be complete through all the gates 55 on one system; but the next gate is so near as to require notice of an approaching engine before the engine reaches this gate. Therefore when this gate is closing it is made to close the circuits at 115 and 116, whereby the 60 gap is bridged directly, so that the current passes on and the closing of the next gate takes place. This operation will be repeated

as far as the bridging is carried out, each succeeding gate starting to close when its predecessor is near the closing-point; but if the engineer chooses not to close the second gate he throws off the switches that would otherwise continue the operation.

If for any reason the engineer wishes to stop the closing of the gate after it has begun, 75 he may reverse all the connections which effect that action and cause the gate to reopen from that point by first disconnecting switches 20 and 23 from whichever wires they were in circuit with; also, he disconnects switch 17 80 and sets switch 22 in connection with wire 28, which completes the circuit from generator 10 over wire 169, rheostat 11, switch 13, wire 31, trolley 33, rail 40, wires 145, 146, and 147 to electromagnet 91, and return over wires 148 85 and 149, rail 41, trolley 34, wire 30, switch 22, and wire 24 back to the generator. The magnet 91 being thus energized attracts armature 92, which pulls on the upper arm of elbow-lever 66 by means of spring 94 and rod 93. 90 This raises rods 71 and 63 and lever 58, breaks the acting circuit by opening switch 50 53, and stops the gate, closes switches 47 49 and 50 52, and sets switch 61 56 ready for engagement. Now the stopped gate may be raised 95 and reopened in full by first turning switch 22 off from wire 28, which cuts out the magnet 91 and releases armature 92 and permits elbow-levers 58 and 66 to be returned by spring 60 and the switch 61 56 to be engaged. The 100 turning off of switch 50 53 and turning on of switches 50 52 and 47 49 reversed the direction of the current to the motor. Now by turning on switch 17 the circuit is completed to the generator, as before described, and the 105 motor is actuated to raise the gate. It will be understood by this that the means of controlling the action of the motive parts is so complete that the gate may be closed or opened or the action of either operation may be suspended and reversed at any point at the will 110 of the engineer.

Should anything occur to prevent the engineer from opening one or more gates when passing, he can open all such in one series at 115 one operation, as follows: Let us suppose that the gates have all been put down and all hand-switches of the system open. The first movement for the engineer is to connect switch 13 with rheostat 11; second, to set switch 22 on 120 wire 29, thereby completing a circuit from generator to motors of all the gates thus: from generator 10 over wire 169, rheostat 11, switch 13, wire 31, trolley 33, continuous rail 40, and wires 145 146 to magnet 130, and returning over wire 153, switch 100 103, wires 151 152, continuous rail 42, trolley 35, wire 29, switch 22, and wire 24 to generator. This energizes magnet 130 and draws pin 97, from which time the action is in all respects the 125 same as that first described for opening one gate, with the exception that in this instance both the outgoing and return currents are over continuous rails, so that any impulse

given to one switch would be given to all in like condition in that system. The bell 133, connected with the circuit of magnet 86, will be sounded when that magnet is energized to 5 perform its part in closing a gate, and bell 134 is connected with circuit of magnet 88, to be sounded when that magnet is energized, for sounding alarms at the crossing by engines coming from either way. 95 is a lever one 10 arm of which projects over the disk 3 to the path of stud 98, the other arm being arranged to contact with a spring 99 as a switch for connecting the wires 113 and 114, which come 15 from a battery in signal-box 108. 109 is a bell, and 110 is an annunciator connected by a rod 111 with mechanism in box 108. When 20 the gate reaches the point of being closed, the pin 98 on disk 3 comes against lever 95 and closes the switch with spring 99, whereby the circuit of the battery in box 108 is closed, and the bell 109 is thereby sounded one stroke and the annunciator 110 is set to show the sign "Closed." This sign will remain until the 25 gate opens, when pin 97, nearing the end of its return path, comes against the lever 95 and opens the switch, when the annunciator will be changed to show the sign "Open."

A bell and annunciator for each gate may be located in the office of any person whose 30 duty or desire it is to note the operation of the gates, and its operation is dependent only upon the movements of the gate and its own battery entirely independent of control by the engineer, whereby careful watch may 35 be maintained at a point distant from the gates over the gate operation as a check against carelessness of the engineer. 135 136 represent lamps to be located upon the gate-arm, one being connected with the electric 40 circuit of one side of the gap and the other with the other side, whereby an engine at either side of the gap will be in electric communication with one of the lamps and keep it lighted when the gate is in operation.

45 Instead of a generator being used upon the engine to produce electricity the wires 21, 24, 169, and 170 may be connected with a storage battery, with trolley connections leading to a local generator or with any other source 50 of electricity.

Any style of rails or wires and any means 55 of making rolling or sliding contact therewith may be substituted for the rails and trolleys shown. The operator's switchboard need be only a few inches square and may be located at any point in the pilot-house of an engine convenient for the engineer to reach it.

By means of this invention an engineer upon his engine while it is running either forward or backward or standing still may open or close one or more gates ahead of him or behind him at will. One gate may be entirely closed, while one is going up and another going down. Parallel tracks may be connected by wires, so that one set of gates an-

swers for a double-tracked road, and the operating mechanism is not otherwise increased.

Having thus fully described my invention, what I believe to be new, and desire to secure by Letters Patent, is the following:

1. A railway-gate, a disk, and a segment of a worm gear-wheel all fixed upon a rotary shaft; a worm for the said gear; a local motor connected with the worm; a switchboard adjacent to the said disk, and mounted on the switchboard, an electromagnet 86, an armature 87, a rod 80 provided with wedge 81, a contact-spring 83, an elbow-lever and switch 66 for contact with spring 83, a switch-spring 53 and a lever 50 therefor mechanically connected with lever 66; and electrical connections between the parts on the switchboard, also between the motor, the switches 50 and 66 and the magnet 86 and a source of electric energy, substantially as described. 85

2. The elbow-lever 66 and connections described for setting switches to close the gate, and a disk mounted on the gate-shaft and carrying a stud to engage the lever 66 and reverse it, substantially as described. 90

3. The elbow-lever 66 and connections described for setting switches to close the gate; a disk mounted on the gate-shaft and carrying a stud to engage lever 66, and having a segment 129; a retaining-lever 54, and connections between it and the lever 66, and a detent 57 to be engaged by segment 129 whereby the operative parts are held with the gate closed. 95

4. The retaining-lever 54, and means for 100 setting it as described; a movable switch-arm 61 and the switch-spring 56 upon lever 54 located to be set in the path of arm 61 when the lever 54 is set, and means for moving the lever 61 into contact with the said spring 56, 105 substantially as described.

5. The elbow-lever 66; the disk 3; the magnet 130 on the disk, the armature 131 carrying the stud 97; the switch 54 and spring 56; the elbow-lever 58 having the insulated arm 110 61 and engaging the lever 66 and provided with a return-spring 60, and electrical connections, substantially as described, whereby the lever 66 is disengaged from the stud 97, both levers returned to place and switch 61 115 set in contact with spring 56.

6. The elbow-lever 66; a disk 3 carrying a pin 97, on the gate-shaft; the switch 50 having two contact-arms; the spring 53 opposite one of the said arms and the spring 52 opposite the other arm; the switch 54; the rods 71 and 63 connecting the lever 66 with switches 50 and 54; and the lever 58 engaging lever 66 and provided with an insulated arm 61, substantially as described, whereby the 120 switches named are set for reversal of the electric current as the gate comes to a close. 125

7. The elbow-lever 66; the spring 83 fixed to the switchboard to contact with the said lever; a rod 77 provided with a wedge 81 to 130

engage spring 83, and having loose connection with the lever 66, and having a stud 79; the rod 71 connected with lever 66, and the elbow-lever 85 connected with the said rod to engage stud 79, substantially as described.

8. The rod 63 and the switches connected therewith; the lever 64 connected with said rod; the elbow-lever 105 having the spring-arm 106 engaging lever 64; the operating-disk 3 upon the gate-shaft and the stud 102 on the disk to engage lever 105 at the end of the opening of the gate for restoring the switches, substantially as described.

9. The disk 3 with the segment 128 on it; the lever 105 and connections described and the spring-detent 107 in the path of segment 128, to retain the said lever, substantially as described.

10. The magnet 88; switch-spring 117; the disk 3 having a segment 127 to engage spring 117; the armature 89; the lever 66; the connecting-rod 90; the switch 74, and connecting-rod 72; the switch-spring 76; an electrical generator and the circuits described including the rail 44' parted from rail 44, substantially as described.

11. Electrical switches, magnets, a motor and connections for operating a railway-gate; insulated rails located in pairs on the road-bed; one of the said rails of each pair being parted at the gate-crossing, and connection between the two parts of the rail and the said

switches whereby the parting may be electrically bridged, substantially as described.

12. A gate-operating segment 3; a magnet 35 130 and connections thereon; a magnet 91 on the gate-switchboard; the elbow-lever 66 and the mechanism operated by it, including lever 58 and its return-spring 60; the armature 92 and connecting-rod 93 and spring 94, connected with the reversing-arm of lever 66, substantially as described.

13. The disk 3; the magnet 130 and stud 102 thereon; the switch 100 having one arm in the path of the said stud, and a spring 103 to contact with the other arm; and rail connections and connecting-wires, substantially as described.

14. Electrical railway-gate-operating mechanism including a stud 98 mounted to move 50 with the gate, a lever 95 in the path of the stud, and a spring 99 to contact with the lever, and a signaling device located at a distance from the gate and provided with a local generator and a local circuit which is connected with the lever 95 and spring 99, whereby by the operation of the gate may be noted independent of gate-operator's control.

In testimony whereof I affix my signature in presence of two witnesses.

THOMAS OLIVER COOPER.
